UNITED STATES PATENT OFFICE.

JAMES KEMNAL, OF CHISLEHURST, AND JOHN HENRY, OF NORBURY, LONDON, ENGLAND, ASSIGNORS TO THE BABCOCK & WILCOX COMPANY, OF BAYONNE, NEW JERSEY, A CORPORATION OF NEW JERSEY.

STEAM SUPERHEATER.

Application filed February 4, 1919, Serial No. 274,840, and in Great Britain May 22, 1918. Renewed October 8, 1924.

Our invention relates to improvements in steam superheaters, applicable more particularly to boilers of the locomotive type, though also applicable to boilers of the 5 marine or other types.

One object of the invention is to insure ready accessibility of all parts, including fire tubes and superheater tubes, for cleaning or repair.

10 Another object is to provide a construction of superheater which is easy to control, is simple to manufacture, presents a minimum number of joints to be kept tight, and by which the degree of superheat can be 15 regulated.

Yet another object is to provide a construction of superheater including receivers disposed horizontally in the smoke box transversely of the length of the main inlet and 20 outlet boxes by means of which receivers the heating surface capacity can be increased without interference with the main inlet and outlet boxes, said receivers being connectible to the boxes and to the superheater tubes in 25 such wise as to permit convenient removal of one or more sections of the superheater without interference with the main boxes or with other superheater sections; the several sections being adapted for convenient handling or for shipment as self-contained units. 30

Still another object is to provide a construction in which the main inlet box is always open to saturated steam, the steam regulator being fitted to the superheated 35 steam box; the arrangement being such that the superheater is always traversed by the full quantity of steam which passes to the engine cylinders when the regulator is open, but which may pass back to the boiler when 40 the regulator is closed; the maintenance of the passage of steam through the superheater preventing liability to overheating.

Yet another object is to provide a construction which permits admission of a small 45 jet of steam to the end of the regulator valve when the regulator is closed, so as to equalize the pressure on the valve and to permit the passage of a limited volume of steam to the engine cylinders for warming purposes—for example, when the engine is 50 standing.

Other objects and advantages will appear from the following description.

In the accompanying drawings, Fig. 1 is a longitudinal section of a steam superheater and associated parts, showing the regulator in open position; Fig. 2 is a view similar to Fig. 1 showing the regulator in closed position; Fig. 3 is an end view of Fig. 1; Fig. 4 is a sectional view, similar to Fig. 1, showing a modified arrangement, in which a larger number of superheater tubes are disposed within each of several large fire tubes; Fig. 5 is an end view of Fig. 4; Fig. 6 is a longitudinal section, showing a modified form of my invention, in which a valve of known form is located in the steam dome; Fig. 7 is an enlarged view similar to Fig. 1, and Fig. 8 is a fragmentary section similar to Fig. 7 but showing the parts in position 70 to admit saturated steam to the engine cylinders.

Similar reference characters denote similar parts in the several views.

Referring, first, to the construction shown 75 in Figs. 1 to 3, A denotes the main saturated steam inlet box, and B the main superheated steam outlet box, both boxes A and B being disposed crosswise in the smoke box. The main inlet box A is connected up to the 80 boiler by means of short tubes C, the latter being expanded in the header A and the boiler tube plate, and connected on the boiler side to one or more dry pipes, preferably fitted in the steam dome, or located 85 near the highest portion of the boiler where there is no steam dome. No valves are connected with the dry pipes, so that steam is continuously admitted into the box A.

Expanded in the boxes A and B are nipples D, also expanded into the upper halves of double-cupped receivers E, or receivers having separate compartments, which extend horizontally in the smoke box in a direction transverse to the length of the boxes 90 A and B. In practice, the upper and lower halves of said receivers E are preferably each stamped or pressed out in one piece.

The superheater tubes F are expanded into the lower halves of the double-cupped receivers E, each tube being led from one compartment of the respective receiver E into and through one of the fire tubes of the boiler, and thence back to the other compartment of the receiver. The receivers are divided 100 along a plane substantially parallel to the

headers and secured together by suitable flanges.

G denotes the superheated steam regulator, which serves the entire installation and 5 which is fitted on the top of the main outlet box B and connected to the boiler tube plate.

Movable within the casing of the regulator is the piston valve H fitted to the hollow valve spindle H', and controllable by operation of the lever H².

K denotes pipes connecting the regulator to the engine cylinders.

In Fig. 1 the regulator is shown open, permitting the passage of superheated steam 15 from the main outlet box B, by way of the regulator G and the pipes K, to the engine cylinders. In Fig. 2 the valve H is shown in position to close the regulator, so that the superheated steam is shut off from the engine 20 cylinders, but is free to circulate back into the boiler without being throttled.

As shown, the tubular spindle H' is formed adjacent to the valve H with a slot or port I controllable by adjustment of the internal spindle J, fitted with the hand-wheel L.

The slot or port I permits passage of saturated steam into and through the interior of the valve spindle H' to mix with the 30 superheated steam and thus to regulate the degree of superheat.

In the end of the internal spindle J is a narrow passage J' which may be brought into register with the slot or port I, so that, 35 for example, when the engine is standing, a limited volume of steam may be admitted by way of the said passage to the back of the valve H, so as to equalize the pressure thereon, and whence such volume of steam may be 40 led to the engine cylinders for warming the latter.

When saturated steam is to be led to the cylinders for warming purposes and superheated steam excluded therefrom, the piston 45 valve H is moved slightly to the right of the position indicated in Fig. 2 so as slightly to uncover the port leading to the cylinders, and at the same time prevent the free flow of superheated steam to the back of the piston 50 valve, as illustrated in Fig. 8. It will be apparent with the form of valve-operating means disclosed that the tubular stem H', together with its valve H, is susceptible of rotation on its axis, whereby the elongated portion 55 of the valve may be moved from the position shown in Fig. 2 through an arc of 180° or less, thus completely closing the outlet from the box B and opening up a free communication between the steam space of 60 the boiler and the engine cylinder.

The parts above described are preferably all of wrought and solid drawn steel.

As will be evident, the arrangement above described answers entirely the objects of the 65 invention as above set forth.

In the modification of our invention shown in Figs. 4 and 5, the arrangement of the regulator is the same as shown in Figs. 1 to 3, but a larger number of superheater tubes are arranged within each of several large 70 fire tubes than shown in Figs. 1 to 3.

In the modification shown in Fig. 6, a valve G' is within the steam dome, the steam entry being controlled on the inlet side of the superheater.

In the modified forms shown in Figs. 4 and 5, and in Fig. 6, the superheater tubes F are expanded into the lower halves of double-cupped receivers E, which are nipped to the main inlet box A and main outlet box B.

What we claim and desire to secure by Letters Patent of the United States is:—

1. A steam superheater comprising, in combination, main inlet and outlet boxes, a regulator comprising a cylinder fitted to 85 the outlet box and a slide-valve, and a tubular valve-spindle connected to and passing through said valve and exposed to saturated steam, said spindle being provided with a port through said exposed portion communicating with the interior of said spindle, whereby saturated steam may pass directly to the rear of said valve.

2. A steam superheater comprising, in combination, main inlet and outlet boxes, a regulator comprising a cylinder fitted to the outlet box and a slide-valve, a tubular valve-spindle connected to and passing through said valve and exposed to saturated steam, said spindle being provided with a port through said exposed portion communicating with the interior of said spindle, whereby saturated steam may pass directly to the rear of said valve, and means for controlling 95 said port.

3. A steam superheater comprising, in combination, main inlet and outlet boxes, a regulator comprising a cylinder fitted to the outlet box and a slide-valve, a tubular valve-spindle connected to and passing through said valve and exposed to saturated steam, said spindle being provided with a port through said exposed portion for the passage 100 of saturated steam to the interior thereof, and a second spindle arranged within the first and having a slot adapted to be brought into registry with said port.

4. A steam superheater comprising main inlet and outlet boxes, superheater tubes connected to said boxes, a regulator for controlling the flow of superheated steam on the outlet side of the superheater to the engine cylinders, said regulator comprising a cylinder and its piston, the piston being exposed on one side to saturated steam, means for introducing saturated steam to the other side of said piston, the parts being constructed and arranged to admit a mixture of superheated and saturated steam to the engine cylinders in one position of the 110 115 120 125 130

piston and in another position of the piston to exclude superheated steam and to admit saturated steam alone to the engine cylinders.

5. A steam superheater comprising side-by-side main inlet and outlet headers, a receiver extending transversely of said headers and having compartments communicating with the respective headers, said receiver being divided along a plane substantially parallel to said headers into two sections removably secured together, and superheater tubes connected to the respective compartments of said receiver on the side remote from said headers, whereby the superheater tubes and the sections of the compartments to which they are connected may be moved as a unit laterally with respect to the headers.

6. A steam superheater for a steam boiler of the locomotive type and having fire tubes comprising side-by-side main inlet and outlet headers, a receiver extending transversely of said headers and having compartments communicating with the respective headers, said receiver being divided along a plane substantially parallel to said headers into two sections removably secured together, and superheater tubes located in part in the fire tubes of the locomotive and having the ends thereof outside bent away from the axes of said tubes and connected at their ends to the respective compartments of said receiver.

7. A steam superheater for a steam boiler

of the locomotive type having fire tubes comprising side-by-side main inlet and outlet headers, a receiver extending transversely of said headers and having compartments, the compartments of said receivers being connected to the respective headers by nipples, said receiver being divided along a plane substantially parallel to said headers into two sections removably secured together, and superheater tubes located in part in the fire tubes of the locomotive and having the ends thereof outside bent away from the axes of said fire tubes and connected at their ends to the respective compartments of said receiver.

8. A steam superheater for a steam boiler of the locomotive type having fire tubes comprising side-by-side main inlet and outlet headers, a receiver arranged horizontally in the smoke box transversely of said headers and having compartments communicating with the respective headers, said receiver being divided along a plane substantially parallel to said headers in two sections removably secured together, and superheater tubes bent away from the axes of said fire tubes and connected at their ends to the respective compartments of said receiver.

In testimony whereof, we have hereunto signed our names.

JAMES KEMNAL.
JOHN HENRY.
